UNITED STATES PATENT OFFICE.

STEVAN KOVACEVICH, OF BLAIR STATION, PENNSYLVANIA.

PICKHEAD.

1,411,919.

Specification of Letters Patent.

Patented Apr. 4, 1922.

Application filed July 3, 1919. Serial No. 308,459.

To all whom it may concern:

Be it known that I, STEVAN KOVACEVICH, a citizen of the United States, residing at Blair Station, in the county of Allegheny 5 and State of Pennsylvania, have invented new and useful Improvements in Pickheads, of which the following is a specification.

This invention relates to pickheads, and more particularly to a pickhead provided 10 with removable terminal elements or points.

One of the main objects of the invention is to provide a pickhead provided with removable points so that, in the breakage or damage to these points, they can be readily 15 replaced.

A further object of the invention is to provide simple and efficient means for detachably securing the points in position.

Further objects will appear from the detailed description.

In the drawings:—

Figure 1 is a side view of a pickhead constructed in accordance with my invention.

Figure 2 is a section taken substantially on 25 line 2—2 of Figure 1.

Figure 3 is a fragmentary longitudinal section through the means for securing one of the points in position.

Figure 4 is a side view of a hammer-head 30 intended to be substituted for one of the points.

Figure 5 is an outer end view of the same.

Figure 6 is a side view of a blade intended to be substituted for one of the pick 35 points.

The pickhead designated by the numeral 1 is of the usual shape and size and includes the central eye 2 adapted to receive the usual handle, and provided at its opposite sides 40 with outwardly projecting arms 3. Each of the arms 3 is provided, in its outer end, with an inwardly tapering frusto-conical socket which is adapted to snugly receive a correspondingly shaped member 4 projecting 45 from the inner end of the point 5. The outer end of member 4 is of less cross area than the inner end of point 5 thus leaving a shoulder 6 which is adapted to fit snugly against the outer end of arm 3 when the point 50 is in normal position so as to effect a close contact therewith. The member 4 is provided with a vertically extending tapering slot 7 which is adapted to receive a tapering wedge 8, this wedge also extending through aligned 55 slots in arm 3 at the opposite sides of the socket 3^A thereof. As will be noted more

clearly from Figures 1 and 3, the upper end 8^A of wedge 8 is rounded so as to facilitate insertion of the same into the lower tapering slot 3^B of arm 3, the lower end of this wedge, 60 when in its innermost position, being flush with the under face of arm 3.

In practice the member 4 of point 5, is fitted into socket 3^A of arm 3 thus bringing the slot 7 into substantial register with slots 3^B, after which wedge 8 is driven tightly 65 into position as shown in Figures 1 and 3 so as draw the point 5 into tight engagement with the outer end of arm 3. After this has been done, the wedge 8 may be secured 70 in position by a screw 9 which is threaded through the wall of arm 3, this screw having its inner end portion shaped to provide a conical element 10 adapted for engagement through a frusto-conical aperture extending 75 through one side of member 4, the inner end portion of the conical member 10 fitting into a conical recess provided in wedge 8 for this purpose, as shown in Figure 2. This screw acts to effectively secure the wedge against 80 all looseness or play. By loosening the screw the wedge may be readily driven out of the arm 3 and member 4 thus permitting the point 5 to be quickly and easily replaced. In Figures 4, 5 and 6, I have illustrated 85 other forms of tools which may be substituted for the point 5 thus providing a combined pick and hammer or axe, as may be desired. The hammer-head illustrated in Figures 4 and 5 and the cutting member 90 or blade illustrated in Figure 6 are intended to be secured in the arm 3 of the head in the same manner as the points 5 are secured in operative position.

Having described my invention, what I 95 claim is:

1. A pickhead having an arm with a square outer end and containing an inwardly-tapered socket, of rectangular cross-section, extending longitudinally inward 100 from said end and entirely closed on four sides and also containing a tapered aperture extending between opposite sides of the arm and intersecting said socket, and a threaded aperture in one wall of the socket and at 105 right angles to said intersecting aperture, in combination with a detachable point having a square shoulder opposed to the square outer end of the pickhead arm and also having a tapered shank, of rectangular cross-section, arranged in the socket in said arm and in which is a tapered aperture adapted 110

to register with said intersecting aperture of the arm and in which is also a tapered aperture adapted to register with the threaded aperture in the arm, a tapered wedge removably arranged in the apertures of the arm and point shank and having a seat in one of its sides, and a removable screw bearing in the threaded aperture of the arm and having an inner tapered end portion occupying the second-named tapered aperture in the point shank and disposed in the seat in the side of the wedge.

2. The combination of a pickhead arm, a point having a shank, a wedge, and a screw; the shank being socketed and completely

housed in the pickhead arm, and the wedge being socketed in both pickhead arm and shank; and the screw bearing in the pickhead arm and extending through a portion of the shank and into the wedge.

20

3. The combination of a pickhead arm, a point having a shank, and a wedge, said shank being socketed and completely housed in the pickhead arm, and the wedge being socketed in both pickhead arm and shank, of means extending through and engaging said arm and shank and seated in the wedge and detachably securing the same together.

25

In testimony whereof I affix my signature.

STEVAN KOVACEVICH.
